UNITED STATES PATENT OFFICE

HENRY P. BROWN AND PETER FRANK TRUSCINSKI, OF SOUTH ST. PAUL, MINNESOTA

VIOLIN

Application filed March 22, 1930. Serial No. 438,159.

This invention relates to certain structural improvements and refinements embodied in the development of a violin and the primary purpose of the invention is to provide an instrument of this class which is characterized by structural features so designed and mechanically co-related as to afford the means for producing individual, colorful, and rare tone properties.

10 In developing this specific form of violin, we have had in mind the paramount aim of making an instrument which has rare tone qualities irrespective of age and without requiring unusual precision and skill in the graduation and finishing of the instrument.

A predominating factor in the construction of this improved violin is strength and durability in the timber, whereby to provide an instrument which is susceptible of developing 20 a sturdy, impressive, and well-balanced tone, as well as insuring uniform fingering and correct intonation.

The specific structural details for accomplishing these advantages will become more 25 readily apparent from the following description and drawings.

In the drawings:

Figure 1 is a top plan view of a violin (complete) constructed in accordance with the 30 present invention.

Figure 2 is a side or edge elevational view of the same.

Figure 3 is a top plan view of the body proper.

Figure 4 is a bottom plan view of the top.

Figure 5 is a longitudinal view in section and elevation showing the assembled body and top and the internal bracing and sound post construction.

40 Figure 6 is a central transverse section on the line 6-6 of Figure 1.

In carrying our inventive conception into practice, we construct the entire instrument (not including the accessories) from two 45 main pieces of material; namely, the body which is generally represented by the numeral 7, and the top indicated by the numeral 8.

The body 7 is formed in a single piece.

To begin with, we take a block of wood of 50 appropriate texture and proportion. We

have found it expedient and desirable to utilize properly matured, well-seasoned maple wood for the purpose. This piece of wood is gouged out with a suitable tool to form a hollow box-like body of customary internal and external configuration, and embodying the bottom or back 9 and the marginal up-standing rim 10.

At the juncture of the rim and bottom is the customary outstanding flange or bead 11. As shown in top plan view, the neck 12 is integral with the body as is the channel shaped peg box 13 and the terminal head or scroll 14. This body possesses customary configuration in general outline as shown in Figure 3, the difference being that all of the parts 9, 10, 11, 12 and 13 are in wood.

The top 8 of the instrument is in the nature of a lid possessing the customary marginal configuration and formed with the companion oppositely arranged intermediate F holes 15. The curvature of the belly 16 and surrounding area varies according to the discretion of the maker. The complete area of the top is such as to permit it to be seated firmly on the upper edge of the rim 10, and in fact, to extend slightly beyond the edge to permit fastening by glue. It will be noted that this is the only point on the entire instrument which is fastened, and this is through the medium of a special texture of glue.

Formed integral with the central portion of the top 8 and located near the central portion of the bass side is a novel sounding post assembly and bass bar. This bass bar 17 also functions as a brace. It is fastened to the under side of the top inward of the marginal edges thereof and formed integral therewith so as to form the desired clearance and to allow it to be seated into the body 7. It is of longitudinally bowed form.

The three struts 18, 19 and 20 constitute the sounding post assembly. The two upper posts 18 and 19 are integral with the belly 16 and defines the proper position for the bridge 21. Incidentally the bridge is placed on the belly at a point approximately equidistant between the two posts 18 and 19.

The depending lower post 20 is arranged directly beneath the bridge and at a point 100

equi-distant from the two posts 18 and 19. It is formed integral with the crown portion of the bass bar 17. This lower end is not fastened to the back 9 but merely rests lightly thereon in a conventional manner. This internal bracing and post means constitutes a predominating factor which insures a sturdy construction and likewise insures an equally stern and firm tone, free from unnecessary wavering and uncertain vibration.

Incidentally, it is submitted that the elements 17 to 20 inclusive constitute novel vibrations transmitting means which assures a uniform quality of tone due to the equal distribution of strain and stress and the entire absence of undesirable frail joints.

We shall not attempt to delve into the series of the factors which render this instrument susceptible of producing desirable properties and colorful tone effects other than to say that these results are seemingly founded on the two-piece top and body construction and the internal post assembly and bracing means.

For completeness of illustration and description, we have shown in Figures 1 and 2, the accessories such as the tuning pegs 21 located in the peg box, the customary band of strings 22, the tailpiece 23, the retention button 24, and the tail anchoring tie or gut 25. In addition, the numeral 26 designates the finger board. The parts 26 and 23 are preferably of ebony.

We claim:

1. In a violin construction of the class described, a hollow body including a marginal rim, a top fastened on said rim, and a multiple element sounding post assembly comprising a pair of longitudinally spaced upper post portions formed integral with the underside of said top and depending into the body, a third post portion connected with said first named post portions and having its lower end resting on the interior of the bottom of said body.

2. In a violin construction of the class described, a hollow body including a back and rim of conventional configuration, a top overlying the back and fastened to said rim, a longitudinally curved brace bar having integral connection at its opposite ends with the end portion of the top and having its curvate intermediate portion depending into the instrument in spaced relation from the back and top respectively.

3. In a violin construction of the class described, a hollow body including a back and rim of conventional configuration, a top overlying the back and fastened to said rim, a longitudinally curved brace bar having integral connection at its opposite ends with the end portion of the top and having its curvate intermediate portion depending into the instrument in spaced relation from the

back and top respectively, and a triple sounding post assembly comprising a pair of longitudinally spaced upper posts connected integrally with the bar and top at a point adjacent the belly portion of the top and a lower post formed integral with the bar at a point between the two upper posts, said lower post having its lower end resting on the interior of said back.

4. In a violin construction of the class described, a hollow body and top, a longitudinally curved and longitudinally disposed bracing bar connected at its opposite ends with the end portions of the top and having its curvate intermediate portion depending into the body of the instrument in spaced relation to the top and back, and an integral sound post carried by said bar and depending therefrom and resting on the interior of the back of the instrument.

5. In a violin construction of the class described, a hollow body and top, a longitudinally curved and longitudinally disposed bracing bar connected at its opposite ends with the end portions of the top and having its curvate intermediate portion depending into the body of the instrument in spaced relation to the top and back, and an integral sound post carried by said bar and depending therefrom and resting on the interior of the back of the instrument, together with a pair of upwardly extending longitudinally spaced bracing struts spaced from said post and connected at their upper ends to the belly portion of said top.

In testimony whereof we affix our signatures.

HENRY P. BROWN.

PETER FRANK TRUSCINSKI.
